UNITED STATES PATENT OFFICE

DRAGUTIN HERL, OF NIAGARA FALLS, NEW YORK

RAILWAY JOINT CHAIR

Application filed February 19, 1931. Serial No. 517,034.

This invention relates to certain new and useful improvements in railway joint chairs.

The primary object of the invention is to provide a railway joint chair wherein meeting rail ends are retained in a joint chair in the absence of the usual bolt and nut lock devices, the construction being such that the rails are permitted limited movement in expansion and contraction while devices are embodied in the joint chair to reduce vibration of the rail ends therein.

A further object of the invention is to provide a joint chair of the foregoing character wherein tensioned pins associated with the side walls of the joint chair and normally extends into the chair are automatically retracted upon the placing of a rail end in the chair and later received in openings provided therefor in the rail webs to effect retention of the rail end in the chair.

With the above and other objects in view that will become apparent as the nature of the invention is better understood, the same consists in the novel form, combination and arrangement of parts hereinafter more fully described, shown in the accompanying drawings and claimed.

In the drawings:—

Figure 1 is a top plan view of a joint chair constructed in accordance with the present invention with the meeting rail ends seated therein;

Figure 2 is a side elevational view;

Figure 3 is a horizontal longitudinal sectional view taken on line 3—3 of Figure 2 showing the rail end retention pins carried by spring arms on the joint chair and the spring devices for holding the rail ends against vibratory movement;

Figure 4 is a detail sectional view showing one of the spring devices and the rail retaining pins set into a side wall of the joint chair;

Figure 5 is a fragmentary side elevational view of one rail end showing the openings therein to receive the retention pins and the bevelled notch in the web thereof to move the pins outwardly of the inner face of the chair wall during assembly of the rail end in the chair;

Figure 6 is a cross-sectional view taken on line 6—6 of Figure 2; and

Figure 7 is a cross-sectional view taken on line 7—7 of Figure 2.

Referring more in detail to the accompanying drawings, there is illustrated a railway joint chair having meeting rail ends seated therein and so retained in the absence of the usual bolt and lock nut devices, the retaining means for the rail ends being automatically engaged therewith and adapted to be manually operated to effect release of the rail from the joint chair for purposes of repair or otherwise. The meeting rail ends are of similar construction and comprise a base flange 10, a web 11 and a tread 12. One side of the web 11 is provided with an inclined depression 13 extending to the end of the web as shown in Figures 3 and 5, while said web inwardly of the depression 13 is provided with a pair of spaced parallel openings 14, all for purposes presently to appear. As shown in Figures 2 and 5, corresponding sides of the treads 12 of the meeting rail ends are provided with socket members 15 to receive an electrical conductor 16 or the like.

The joint chair comprises a bottom wall 17 having upstanding inwardly directed side walls 18 designed for intimate contact with adjacent portions of the meeting rail ends as shown in Figures 6 and 7, the devices for retaining the meeting rail ends in the joint chair being carried by the latter. Upstanding reinforcing ribs 19 are carried by the side walls 18 of the joint chair and a pair of said ribs at each side of the chair have cut away portions to receive a tensioned arm 20 as illustrated, one end of the arm carrying a finger piece 21 with the corresponding end of the arm spaced from a rib whereby said end may be moved outwardly of the adjacent side wall of the chair by said finger piece 21. A pair of laterally directed pins 22 is carried by the inner side of the free swinging end of the spring arm 20 and projects through openings 23 provided in the adjacent side wall 18 of the joint chair to enter the openings 14 in the rail web as shown in Figures 3 and 6 for retaining the rail ends in the chair. The outer pin 22 of each pair is bevelled as at 22a to cooperate

with the inclined depression 13 of the rail web.

In assembling the rail ends in the joint chair, it being understood that the pins 22 normally project into the interior of the joint chair, the rail ends are moved into the opposite open ends of the chair, the inclined depression 13 riding over the tapered end 22a of the outer pin for moving both of said pins 10 out of the path of movement of the rail ends and when said rail end has been moved a sufficient or proper distance into the joint chair, the pins 22 under influence of the spring arm 20 automatically move into the openings 14 of the rail webs for anchoring the rail end in the chair. When it is desired to remove the rail end, the finger piece 21 of each spring arm 20 is grasped by a suitable implement and moved outwardly of the adjacent side 20 wall of the chair which removes the pins 22 from the rail openings 14 so that the latter may be slid outwardly of the chair.

To prevent vibration of the rail ends in the joint chair and to prolong the life of the construction, spring devices are carried by the side walls of the joint chair and engage the rail webs 11. As shown more clearly in Figures 3, 4 and 7, the inner face of a side wall of the joint chair is provided with a 30 longitudinal depression or groove 24 undercut at its ends to receive the ends of spring strips 25, the intermediate portions of which normally project into the interior of the joint chair and when said rail ends are positioned in the chair, the springs 25 engage the same and operate to reduce vibratory movement of the rails in the chair.

While there is herein shown and described the preferred embodiment of the invention, 40 it is nevertheless to be understood that minor changes may be made therein without departing from the spirit and scope of the invention as claimed.

I claim:—

45 1. In a device of the character described, a railway chair, meeting rail ends seated therein and having openings in the webs thereof, spring arms carried by the sides of the chair, and pins carried by the arms adapted to be received in the rail web openings for the retention of the rail.

55 2. In a device of the character described, a railway chair, meeting rail ends seated therein and having openings in the webs thereof, spring arms carried by the sides of the chair, pins carried by the arms adapted to be received in the rail web openings for the retention of the rail, and cooperating bevelled faces on the inner end of one pin and adjacent rail.

60 3. In a device of the character described, a railway chair, meeting rail ends seated therein and having openings in the webs thereof, spring arms carried by the sides of the chair, pins carried by the arms adapted

to be received in the rail web openings for the retention of the rail, and spring devices on the inner face of the chair to be engaged by the rail ends to reduce vibration of the rails in the chair.

70 4. In a device of the character described, a railway chair, meeting rail ends seated therein and having openings in the webs thereof, spring arms carried by the sides of the chair, pins carried by the arms adapted to be received in the rail web openings for the retention of the rail, cooperating bevelled faces on the inner end of one pin and adjacent rail, and spring devices on the inner face of the chair to be engaged by the rail ends to 80 reduce vibration of the rails in the chair.

5. In a device of the character described, a railway chair, meeting rail ends seated therein and automatically operating interlocking devices carried by the chair and rail ends for retaining the latter in the chair, and spring devices carried by the chair adapted to be engaged by the rails to hold the latter against vibratory movements.

85 6. In a device of the character described, a railway chair, meeting rail ends seated therein and automatically operating interlocking devices carried by the chair and rail ends for retaining the latter in the chair including pins on one member to be received in 95 openings in another member.

100 7. In a device of the character described, a railway chair, meeting rail ends seated therein and automatically operating interlocking devices carried by the chair and rail ends for retaining the latter in the chair including pins on one member to be received in openings in another member, and manually operable means for removing the pins from the openings to permit removal of the 105 rail ends from the chair.

In testimony whereof I affix my signature.
DRAGUTIN HERL.
